SHOWER BATH SPRAY HEAD

Isadore Herzbrun and Charles F. Schultis,
Cleveland, Ohio

Application November 23, 1940, Serial No. 366,894

4 Claims. (Cl. 299—141)

This invention relates to shower bath spray heads, and more particularly a spray head designed to permit the elimination of solid material collecting within the head.

In the use of spray heads of the type in which the water is discharged through small jet orifices, particles of scale, rust, sand, etc. accumulate within the head because of the small size of the orifices and such accumulations of solid material often clog the jet orifices.

It is the object of the present invention to provide a spray forming wall constructed of parts which are relatively movable in such a manner that accumulations of solid material may be quickly discharged from the interior of the spray head.

With the above and other objects in view the invention may be said to comprise the spray head as illustrated in the accompanying drawing hereinafter described and particularly set forth in the appended claims, together with such variations and modifications thereof as will be apparent to one skilled in the art to which the invention pertains. Reference should be had to the accompanying drawing forming a part of this specification, in which:

Figure 1 is a side elevation of a spray head embodying the invention with the lower part of the head broken away and shown in axial section;

Fig. 2 is a bottom plan view of the head viewed as indicated at 2—2 in Fig. 1; and

Fig. 3 is a fragmentary transverse section showing the closure disk in tilted position.

In the accompanying drawing the device of the present invention is shown applied to an adjustable spray head of conventional design which comprises an inlet section 1, which is internally threaded at its upper end to screw onto a water pipe 2 and which has a ball shaped lower end 3, and a bell shaped body 4 which is adjustably mounted on the ball end of the inlet section. The body 4 has an axial inlet opening 5 at its upper end through which the water is delivered into an enlarged chamber 6, a flat shoulder 7 being provided around the inlet 5 at the top of the chamber 6. The upper end of the bell shaped body 4 is recessed to receive the ball end 3 of the inlet section and is clamped in various angular positions on the ball end 3 by means of a threaded clamping collar 8. The mounting of the bell shaped head upon the inlet section is conventional, the improvement of the present invention being concerned only with the

spray device associated with the body 4 of the head.

The bottom wall of the chamber 6 is formed by a threaded cap 9 screwed onto the lower end 5 of the body 4. The cap 9 has a large centrally disposed opening 10 of a diameter corresponding substantially to that of the chamber 6. The opening 10 is so formed as to provide a downwardly tapering, substantially conical seat 11 at 10 the margin thereof. A closure disk 12 is formed to fit in the opening 10, and this disk has the lower portion 13 of its peripheral edge tapered toward the lower face of the disk, tapered portion 13 being preferably concave in transverse 15 section. The upper portion 14 of the peripheral edge of the disk is preferably formed on a taper reverse to that of the portion 13, the tapered surfaces 13 and 14 converging to a seating edge 15 which is adapted to engage the tapered seat 11 intermediate the top and bottom thereof. The disk 12 closes the opening at the bottom of the head except for spaced orifices 16 which are provided between the margins of the opening 10 and disk 12. As herein shown, the orifices 16 20 are formed by spaced notches in the periphery of the disk.

The orifices 16 are of small diameter so that fine jets of water are discharged at relatively high velocity during operation of the shower head. By pressing upwardly on the under surface of the disk 12 at the center thereof, the disk 12 may be lifted off the seat 11 against the pressure of the water within the chamber 6. If the upward pressure be applied at one side of the axis of the disk, the disk will be tilted laterally to a position such as shown in Fig. 3 of the drawing to permit free flow of water from the chamber 6 over the face of the disk and over the notched periphery thereof, as well as over the tapering seat 11, and such flow of water will quickly wash away any accumulation of solid material which may have collected within the chamber 6. The seating edge 15 of the disk is of greater diameter than the lower end of the opening 10, so that the disk cannot be removed downwardly through the opening. The disk, however, is free to tilt in the opening to a position such as shown in Fig. 3, in which the edge 15 bears upon the seat 11 at diametrically opposite points and nearly half of the disk projects below the bottom of the spray head. The upper bevel 14 of the disk 12 facilitates the pivotal movement of the disk on the seat 11 and prevents interference between the upper edge of the disk 12 and the lower edge of the seat 11 when

the disk is returned from tilted to normal position.

The disk 12 is preferably backed by a spring within the chamber 6 which serves to normally hold the disk seated in the opening 10, but which is yieldable to permit the disk 12 to move upwardly in an axial direction or to tilt laterally in any direction about a transverse axis.

As herein shown, the disk 12 is provided with a central projection 17 on its upper side which fits within one or more of the coils at the small end of a conical coil spring 18 within the chamber 6. The large upper end of the spring 18 is seated upon the shoulder 7 at the top of the chamber 6. The spring 18 will readily yield in an axial direction when pressure is applied to the center of the disk and will yield laterally as illustrated in Fig. 3 when pressure is applied to the bottom of the disk between its center and periphery. When the disk is tilted to a position such as shown in Fig. 3, the pressure of the spring 18 and of the water flowing through the head will hold the disk in the tilted position until it is returned by pushing upward on the downwardly projecting edge portion of the disk. The beveled upper edge 14 of the disk permits the downwardly projecting edge of the disk to readily pass back into the opening 10, and when the disk is returned to substantially horizontal position it snaps into engagement with the seat due to the pressure of the spring 18. The concave edge portion 13 of the disk establishes communication between adjacent jet orifices so that the orifices are not as readily clogged as where the water is discharged through unconnected orifices.

It is apparent that the present invention provides a very simple inexpensive and efficient spray head which can be instantly cleaned whenever any of the jet orifices are clogged by an accumulation of solid material.

It is to be understood that variations and modifications of the specific device herein shown and described for purposes of illustration, may be made without departing from the spirit of the invention.

What we claim is:

1. A shower bath spray head having a chamber with an inlet opening and a bottom wall provided with a single large centrally disposed opening, and a closure disk in said chamber having a marginal seating portion engageable with the bottom wall at the margin of said opening, the marginal seating portions of said disk and opening being formed to provide a circumferential row of jet orifices, said disk being movable upwardly and tilttable laterally in said opening upon application of pressure to the under face thereof to dispose diametrically opposite seating portions of the disk clear of the bottom wall with intermediate seating portions of the disk in engagement with the bottom wall at opposite sides of the opening, whereby pressure upon the engaging seating portions retains the disk in tilted position to permit free flow of water past the disk and through the discharge opening to wash away accumulations of solid material from the interior of the head.

2. A shower bath spray head having a chamber with an inlet opening and a bottom wall provided with a single large centrally disposed opening, a closure disk in said chamber having a marginal seating portion engageable with the bottom wall at the margin of said opening, the marginal seating portions of said disk and opening being formed to provide a circumferential row of jet orifices, and a conical coil spring in said chamber for pressing the disk toward said opening, said spring having its large end engaging the top wall of said chamber and its small end connected to said disk centrally thereof, said disk being movable upwardly and tilttable laterally in said opening upon application of pressure to the under face thereof to dispose diametrically opposite seating portions of the disk clear of the bottom wall with intermediate seating portions of the disk in engagement with the bottom wall at opposite sides of the opening, whereby pressure upon the engaging seating portions retains the disk in tilted position.

3. A shower bath spray head having a chamber with an inlet opening and a bottom wall provided with a single large centrally disposed opening and a downwardly tapering seat around the opening, and a closure disk having a peripheral edge adapted to engage said seat, the lower portion of said peripheral edge tapering downwardly and the upper portion thereof being reversely tapered, the edge of said disk having spaced notches which with said seat form jet orifices, said disk being movable upwardly and tilttable laterally in said opening upon application of pressure to the under face thereof to dispose diametrically opposite seating portions of the disk clear of the bottom wall with intermediate seating portions of the disk in engagement with the bottom wall at opposite sides of the opening, whereby pressure upon the engaging seating portions retains the disk in tilted position.

4. A shower bath spray head having a chamber with an inlet opening and a bottom wall provided with a single large centrally disposed opening and a downwardly tapering seat around the opening, a closure disk having a peripheral edge adapted to engage said seat, the lower portion of said peripheral edge tapering downwardly and the upper portion thereof being reversely tapered, the edge of said disk having spaced notches which with said seat form jet orifices, and a conical coil spring in said chamber for pressing the disk toward said opening, said spring having its large end engaging the top wall of said chamber and its small end connected to said disk centrally thereof, said disk being movable upwardly and tilttable laterally in said opening upon application of pressure to the under face thereof to dispose diametrically opposite seating portions of the disk clear of the bottom wall with intermediate seating portions of the disk in engagement with the bottom wall at opposite sides of the opening, whereby pressure upon the engaging seating portions retains the disk in tilted position.

ISADORE HERZBRUN.
